UNITED STATES PATENT OFFICE

2,411,149

CLOSURE FOR SHEET-METAL CONTAINER
OPENINGS

Howard W. Dodson, Philadelphia, Pa., assignor
to United Steel Barrel Company, Philadelphia,
Pa., a corporation of Pennsylvania

Original application July 20, 1939, Serial No.
285,477. Divided and this application August
12, 1943, Serial No. 498,289

1 Claim. (Cl. 220—39)

1

The present invention relates to certain new and useful closures for sheet-metal containers such as steel drums and the like, and it relates more particularly to certain constructions in the openings and the closures therefor whereby said steel or other sheet metal containers may be emptied and refilled.

For the purpose of illustrating the invention, there are shown in the accompanying drawings forms thereof which are at present preferred, since the same have been found in practice to give satisfactory and reliable results, although it is to be understood that the various instrumentalities of which the invention consists can be variously arranged and organized and that the invention is not limited to the precise arrangement and organization of the instrumentalities as herein shown and described.

The present application is a division of my application Serial No. 285,477, filed July 20, 1939, 20 which issued into Patent 2,343,286, on March 7, 1944.

In the accompanying drawings, in which like reference characters indicate like parts,

Figure 1 represents a cross-sectional perspective view of one form of construction embodying the present invention.

Figure 2 represents a fragmentary cross-sectional perspective view of the container of Figure 1 as it appears in an intermediate stage of construction.

Figure 3 represents a cross-sectional perspective view of another embodiment of the present invention.

Figure 4 represents a fragmentary cross-sectional perspective view of still another form of construction embodying the present invention.

Figure 5 represents a cross-sectional perspective view of still another form of construction embodying the present invention.

Figure 6 represents a sectional perspective view showing another embodiment of the present invention.

Figure 7 represents a sectional perspective view of still another embodiment of the present invention.

Figure 8 represents a sectional perspective view of a further embodiment of the present invention.

In the drawings, only a fragmentary portion of one of the sheet-metal walls of the sheet-metal container is shown; it being understood that this sheet-metal wall is generally an end wall of a more or less cylindrical container, although it may be a side wall also. The sheet-metal wall

2

of the container is designated generally by the numeral 20 in all the figures.

In the embodiment of the invention shown in Figure 1, the sheet metal of the wall 20 is provided with a suitable hole, and the sheet metal is then flanged inwardly around the hole as shown in Figure 2 to provide a more or less cylindrical flange 21 formed integrally with the sheet metal of the wall 20. Intermediate the more or less cylindrical flange 21 and the main body portion 20, the sheet metal is also preferably provided with a generally annular rib-like depression 22 or elevation 23 (in the form of construction shown in Figure 1, it is in the form of a depression while in the form of construction shown in Figure 3, it is an elevation). A generally flat annular gasket-seat 24 surrounds the flange 21 in the embodiment of Figure 1 while a generally flat annular gasket-seat 36 surrounds the flange 21 in the embodiment of Figures 3 and 4.

The annular ribs 22 and 23 serve as a stiffening reinforcement around the opening defined by the generally cylindrical flange 21 and also around the generally flat annular gasket-seat 24 which surrounds the generally annular flange 21 in the embodiment of Figure 1 or around the flange-base portions 25 in the forms of construction shown in Figures 3 and 5; all the above named portions, namely the flange 21, the gasket-seat 24 and the reinforcing ribs 22 or 23 and flange-base 25, being formed integrally with each other and drawn or pressed out of the same metal as that of which the body 20 is formed. 35 The sheet metal 20 may be of 12 to 26 gauge sheet-steel.

The flange 21 is then threaded by means of two or more coacting thread-forming rolls (of the form well known in the art) by means of 40 which the metal of the flange 21, which is initially in the form shown in Figure 2, is de-formed in such a way that a thread 26 of the character shown in Figure 1 is produced. This thread (26) differs essentially from the rounded-cross-section thread commonly rolled onto the discharge spout of tin cans, in that the rolled thread on tin canned flanges is produced merely by bending the sheet metal, whereas the thread 26 hereinabove indicated is produced by an actual deformation or flowing of the comparatively heavy gauged sheet-steel under the pressure of the thread-forming rolls, to form a more or less sharp thread.

A plug 27 of cast metal or die-cast metal, or a 55 plug, like plugs 28, 29, 30 or 32, pressed out of

sheet metal is provided with a cast thread or with a cut thread 33 as in Figure 1 and with a rolled thread 34 as in Figures 3, 4, 5, 6, 7 and 8 (formed in the same manner as the thread 26), corresponding generally to the thread 26 of the flange 21, and having a laterally extending flange 35, in juxtaposition to the gasket-seats 24 and 36 and adapted to engage the annular sealing gasket 37 between itself and the gasket-seats 24 and 36, respectively, so as to form a fluid-tight seal. The cavity 38 in the plug 27 may be of any suitable non-circular cross-section, as for instance, square, hexagonal, or triangular, for the reception of a wrench or other instrument by means of which the plug may be turned.

In the form of construction shown in Figure 1, the annular wall portion 45 of the annular reinforcing rib 22 (that is, the portion of the sheet-metal wall directly adjacent to the gasket-seat 24) is turned or formed or spun inwardly slightly so as to form a shoulder against which the flange 46 of a thin sheet-metal tamper-proofing cap 34 may be crimped inwardly, so as to prevent the removal of the plug 27 without detection.

In the embodiment of the invention shown in Figures 3 and 4, the annular reinforcing bead or rib 23 is raised upwardly intermediate the main body portion 28 of the sheet-metal wall of the container and the annular portion 25 which forms a base for the upwardly extended bung-flange 21 in the form of construction shown in Figures 3 and 4 (and also for the form of construction shown in Figure 6).

The bung-flange 21, in the forms of construction shown in Figures 3 and 6, is extended upwardly from the basal portion 25, and can be terminated in a more or less sharp or flattened edge 36 constituting a gasket-seat as in Figures 3, 6 and 7.

It should be understood that the screw-thread on the bung-flange 21, in each of the modifications shown in Figures 3, 4, 5, 6, 7 and 8, is formed in the same manner as hereinabove indicated with respect to Figures 1 and 2, namely, by deformation or swaging the metal into the screw-thread formation.

The pressed or stamped sheet-metal plugs 28, 29, 30, 31 and 32 are formed in generally cup shape; the plugs 28, 29, 31 and 32 being "cupped" generally downwardly while the plug 30 is cupped generally upwardly. A transverse rib 48 may be pressed out of the central or more or less flat portion of the cup-shaped plugs 28, 29 and 30, either extending entirely across the diameter thereof, or extending only across a part of the diameter thereof, whereby the plug may be engaged by a suitable tool such as a wrench, pliers or the like, or as in the case of the rib 49 in Figure 6, it may be engaged by any flat object such as a wide screw driver or any flat piece of metal. If desired, a solid metallic rib 50 may be extended across the flat part of the plug and spot-welded thereto or otherwise secured thereto, for the same purpose as in the plug 32 of Figure 7.

The plugs 28, 29, 30 and 32 may also be provided with gasket-confining flanges, as for instance, the annular flanges 51 shown in Figures 3 and 5, or by the inwardly crimped flange 53 shown in Figure 7, or, as in the case of the type of plug 30 shown in Figure 6, the central part of the plug may be depressed to form the inner gasket-confining flange 54. By this means, the gasket 37 is not only confined in a generally axial direction, but is also confined in a generally radial

direction so as to prevent its spreading unduly and thereby loosening the "seal."

The relationship of the gasket-confining flanges 51 and 53 might be either that indicated in Figures 3 and 7, where the flange extends below the gasket-seat 24 or 36, or it may be that illustrated in Figure 5 where it extends only down to the depth of the gasket 37. The gasket-confining flanges may also be provided on the cast plugs, such as the cast plugs 27 indicated in Figure 1, by merely extending the cast metal portions downwardly, that is, by extending a downward gasket-confining flange from the lateral flange 35 at a diametral point just sufficient to clear the outer diameter of the gasket 37.

In the form of construction shown in Figure 6, the axial distance or axial extent of bung-flange 21 and of the threaded portion of the plug may be so related or proportioned as to be substantially equal, thereby permitting the interposition of a second sealing gasket 55 between the lower periphery of the threaded portion 34 of the plug and the flange-base portion 25, as indicated in Figure 6.

The tamper-resistant cap 56, shown in Figure 3, may be crimped inwardly against the outer surface of the threaded flange 21 as at 57. As shown in Figure 3, the cap 56 (which is of readily-deformable material such as very thin sheet metal or the like) is somewhat over-size relative to the bung 28 so that an annular radial clearance is provided therebetween; it being impossible to remove the cap 56 from about the bung opening without substantial deformation of said cap. In Figures 5 and 6, two further alternative forms of tamper-resistant cap arrangement are shown. In Figure 5, the tamper-resistant cap 58 is an outwardly flared skirt portion 59 which is adapted to be snapped into or to be spread out into the annular inwardly enlarged portion 60 formed intermediate the inclined portion 61 and the main body portion 28 of the sheet metal of the container. The tamper-resistant cup 62 shown in Figure 6 (likewise formed of thin sheet metal) is on the other hand provided with the inwardly crimped skirt 63 which is crimped around the undercut outer shoulder 64 of the raised rib 23.

In the form of construction shown in Figure 7, the down-turned flange 53 of the plug is also threaded to engage one or more turns of the thread 26 of the bung-flange 21.

In Figure 8, there is shown another embodiment of the present invention in which the stiffening rib 23 is pressed outwardly and surrounds the gasket-seat 24; the rib 23 serving radially to confine the gasket 37 when the latter is compressed by the shoulder 35 of the plug 29. The inwardly crimped skirt 63 of the tamper-resistant cap 62 is crimped around the undercut outer shoulder 64 of the rib 23 as in the embodiment of Figure 6.

It will be understood that the various features illustrated in the several figures of drawings may be interchanged with the corresponding features shown in modifications illustrated in other figures of the drawings.

The present invention may be embodied in other specific forms without departing from the spirit or essential attributes thereof, and it is therefore desired that the present embodiments be considered in all respects as illustrative and not restrictive, reference being had to the appended claim rather than to the foregoing description to indicate the scope of the invention.

Having thus described the invention, what I claim as new and desire to protect by Letters Patent is:

In a sheet metal container, a generally cylindrical bung-flange drawn integrally from said container and defining an opening in a wall thereof, said bung-flange extending outwardly from said wall and providing a gasket seat at its outer end, said bung-flange being helically corrugated to provide an internal screw-thread and an external screw-thread thereon, an annular gasket disposed upon said gasket-seat, a screw-threaded bung operatively engaged with the internal screw-

threads of said bung-flange, said bung having an annular transversely-extending shoulder formed thereon for compressing said gasket upon said gasket-seat, said shoulder having an annular flange formed thereon for enclosing said gasket seat and for confining said gasket therewithin, and an over-size tamper-resistant cap of readily deformable material fitted over said bung and said bung-flange and generally spaced apart therefrom, said cap being crimped against the external screw threads of said bung-flange and being incapable of removal without deformation.

HOWARD W. DODSON.
